UNITED STATES PATENT OFFICE

WILLIAM D. FERRIS, OF STERLING, ILLINOIS, ASSIGNOR TO FRANTZ MANUFACTURING CO., OF STERLING, ILLINOIS, A CORPORATION OF ILLINOIS

DESIGN FOR A LATCH

Application filed July 25, 1930. Serial No. 36,478. Term of patent 14 years.

To all whom it may concern:

Be it known that I, WILLIAM D. FERRIS, a citizen of the United States, and resident of Sterling, in the county of Whiteside and State of Illinois, have invented a new, original, and ornamental Design for a Latch, of which the following is a specification, reference being had to the accompanying drawing, forming a part thereof.

Fig. 1 is a view looking down on the latch, showing my new design.

Fig. 2 is a front elevation of the latch in locking position.

Fig. 3 is a similar view showing the latch in unlocking position.

I claim:

The ornamental design for a latch, as shown and described.

Sterling, Illinois, July 21, 1930.

WILLIAM D. FERRIS.
